UNITED STATES PATENT OFFICE

136,749

DESIGN FOR A BADGE OR SIMILAR ARTICLE

Arthur H. Cadman, Orange, N. J., assignor to Breeze Corporations, Inc., Newark, N. J., a corporation of New Jersey

Application April 12, 1943, Serial No. 109,956

Term of patent 14 years

to all whom it may concern:

Be it known that I, Arthur H. Cadman, residing at 210 Central Avenue, Orange, Essex County, State of New Jersey, have invented a new, original, and ornamental Design for a Badge or similar article, of which the following is a specification, reference being had to the accompanying drawing, forming part thereof.

I claim:

The ornamental design for a badge or similar article, as shown.

ARTHUR H. CADMAN.
